Primary Examiner—Alan P. Douglas*Assistant Examiner*—Caron D. Veynar*Attorney, Agent, or Firm*—Nawrocki, Rooney & Sivertson[57] **CLAIM**

The ornamental design for a handle for a knife, as shown and described.

DESCRIPTION

FIG. 1 is a top plan view of a handle for a knife having ornamental design in accordance with the present invention; FIG. 2 is a front view thereof, the rear view being a mirror image thereof;

FIG. 3 is a bottom plan view thereof;

FIG. 4 is a left side view thereof;

FIG. 5 is a right side view thereof;

FIG. 6 is a cross-sectional view thereof taken along line 6—6 of FIG. 1;

FIG. 7 is a cross-sectional view thereof taken along line 7—7 of FIG. 2;

FIG. 8 is an exploded front view thereof with the cap removed;

FIG. 9 is a front view thereof, the broken line showing of a blade is for illustrative purposes only and forms no part of the claimed design;

FIG. 10 is a front perspective view thereof; and,

FIG. 11 is a rear perspective view thereof.
